FLUID PREHEATER

Nathan A. Arvins, Brooklyn, Abraham A. Arvintz, Hollis, and Robert A. Arvintz, New York, N. Y., assignors to Arvins Viscolator Corporation, Brooklyn, N. Y., a corporation of New York

Application January 29, 1952, Serial No. 268,846

10 Claims. (Cl. 219—38)

1

This invention relates to fluid heaters, wherein a fluid is circulated through a heat exchanging unit for delivery to a predetermined point of discharge and, further, wherein air is circulated through a coil and heated by the same heating medium for transmission to the same point of discharge, as with paint, lacquer and similar preheaters of the type generally known in the art.

More particularly, the invention deals with a heater unit having an arrangement of straight fluid circulating coils disposed in a heat conducting body and so mounted in the casing of the apparatus as to facilitate cleaning of the respective tubes without disturbing arrangement of the tubes in the casing.

The novel features of the invention will be best understood from the following description, when taken together with the accompanying drawings, in which certain embodiments of the invention are disclosed and, in which, the separate parts are designated by suitable reference characters in each of the views and, in which:

Fig. 1 is a longitudinal section through a heater made according to our invention, with part of the structure broken away and shown in a right angle section.

Fig. 2 is a plan view of the structure, as seen in Fig. 1, with parts of the construction broken away and in section.

Fig. 3 is a bottom plan view of the structure, as seen in Fig. 1, with parts of the construction broken away and in section.

Fig. 4 is an enlarged detail sectional view, showing a modified arrangement of air coil mounting; and

Fig. 5 is a view similar to Fig. 4, showing another modification.

In Fig. 1 of the drawing, we have shown a heater comprising an elongated tubular casing 10, to the lower end of which is secured a header 11, having circumferentially spaced supporting feet 12 on an outwardly extending flange portion 13 of the header. At upper and lower ends of the tubular casing 10 are tube plates 14 and 15, with which a series of circumferentially arranged fluid circulating tubes 16 are secured.

Secured to the upper header or plate 14 is an upper cap or closure plate construction 17, having an outwardly extending flange 18 of similar diameter to the plate or flange 13 and adapted to support an outer tube or jacket 19. Mounted in the closure plate 17 is an elongated electric cartridge heater tube 20, having terminals 21 and 22 disposed within the chamber 23 of the closure plate 17. Also mounted in the closure plate 17 is an aquastat 24, the circuit wires 25 of which are in circuit with the terminals 21 and 22 and with a light bulb unit 26 mounted on one wall of the cover plate 17, as clearly indicated in Fig. 2 of the drawing. This circuit is such that the aqua-

2

stat will indicate temperature of the preheater; whereas, the light bulb 26 will indicate externally of the heater that the heating unit is in operation or, in other words, that circuit is completed to the cartridge heater 20' arranged in tube 20.

Disposed in the casing 10, around the circulating tubes 16 and the cartridge heater 20' and aquastat 24 is a body of heat conducting material 27, preferably formed from aluminum which can be moulded or otherwise formed around the tubes 16, 20 and aquastat 24 and then arranged in the casing 10. This construction will provide an efficient means of conducting heat from the heater cartridge 20' to the tubes 16, then to the casing 10 and, thus, to an air coil 28 encircling and contracting the upper portion of the casing 10. This coil 28 has intake and discharge ends 29 and 30, note Fig. 3, which extend from suitable fittings 31 and 32, respectively, with which ends of the coil 28 couple.

The coil 28 is contained within a suitable housing, or casing, 33 which may be in the form of aluminum foil, asbestos cloth, or the like, to protect the coils in the operation of inserting glass-wool insulation 34 into the chamber between the casing 10 and jacket 19 and outwardly of the housing 33. This insulation also facilitates heat conductivity to the air coil 28, as will be apparent.

The top wall of the header 11 has apertures 36, registering with the tubes 16, and the cap 17 has similar apertures 37, registering with the upper ends of the tubes 16. The last named apertures open into an annular chamber 38, controlling bypassing of the fluid circulating through one group of tubes 16 and to another group thereof, this chamber being closed by a ring plate 39. It will appear from Fig. 1 of the drawing that the terminals 21 and 22 and the outer end of the aquastat are disposed within the chamber 23. This chamber is closed by a detachable cover plate 40.

The header 11 has a downwardly extending partition 41 which divides the header into an intake chamber 42 and an outlet chamber 43; note also, in this connection Fig. 3 of the drawing. The chambers 42 and 43 are closed by a detachable plate 44 secured to the bottom of the header, but disposed at a point above the depending feet 12. The plate 44 has plugs 45 arranged in alignment with the apertures 36 and similar plugs 46 are disposed in the ring 39, so as to facilitate clean-out of the tube 16 without displacing the header 11, plate 44 and ring 39, the cover plate 40 being removed when this operation is performed.

Arranged between the casing 10 and jacket 19 at one side of the header and disposed within the compartment in which the insulation 34 is arranged is an electric conduit 47, which opens into the chamber 23, or a side extension 23'

thereof, as seen in Fig. 1. The extension 23' is closed by a plug 48. The lower end of the conduit 47 couples with an electric fitting 49 opening out through the jacket 19, the fitting having a removable plate 50 to gain access to the interior of the fitting and a tubular discharge 51, through which the circuit wires, which service the heater, aquastat and lamp, pass, as will be clearly apparent. The fitting 49 is supported upon the flange extension 13, as will be apparent.

Considering now Fig. 3 of the drawing, it will appear that extending into the header 11 is an inlet fitting 52, by means of which fluid to be heated can be introduced into the chamber 42 and, at 53, is shown a similar outlet fitting for discharging the fluid from the chamber 43. In the event of a build-up in pressure at the discharge end, we provide another fitting 54 exposed to the chamber 43, from which fluid can be returned to a source of supply. It will be understood, in this connection, that, in most instances, the fluid to be heated, such as paint, lacquers and the like, have a forced circulation through the heating apparatus. In this connection, it will be apparent that the extended passage of the fluid through the long circulating tubes 16 will provide an efficient operation of the heater.

In Fig. 4 of the drawing, we have shown a modified mounting of the air coil in the heater and, in this figure, 19' represents the outer jacket; 10' the casing; 16' one of the circulating tubes; 27' the heat conducting body and it will here be noted that the air coil 28' is disposed within the casing 10 and embedded in the body 27', rather than being disposed outwardly of the casing 10, as in Fig. 1.

In Fig. 5 of the drawing, we have shown a further modification, wherein 19'' represents the outer jacket; 16'' one of the fluid circulating tubes; and at 28'' the air coil. With this construction, the casing 10 is dispensed with and a heat conducting body 55, similar in characteristics to the heat conducting body 27, is employed, with the exception that means will be provided to receive the coil 28'' on the surface of the body 55. This means comprises peripheral grooves, as at 56, in the body 55.

For sake of clarity in the showing, it will be noted that, at the lower part of Fig. 1 of the drawing, part of the structure is broken away to show the cross-section of the partition 41 at right angles to the showing in Fig. 1 or, in other words, consistent with the showing in Fig. 3 of the drawing.

Having fully described our invention, what we claim as new and desire to secure by Letters Patent is:

1. A fluid heater of the character described, comprising a tubular casing having an insulated jacket encircling and spaced therefrom, a plurality of fluid circulating tubes extending longitudinally of and disposed within said casing, means for by-passing fluid from one group of tubes to another at one end of the casing, the other end of the casing having intake and discharge chambers communicating with said different groups of tubes, means for controlling intake and discharge of fluid with respect to said intake and discharge chambers, a heater disposed in said casing and arranged longitudinally with respect to said tubes, said heater and tubes being enveloped in a body of heat transmitting material, and means providing access to opposed

open ends of the circulating tubes without disturbing mounting of the several casing parts of the heater.

2. A fluid heater of the character described, comprising a tubular casing having an insulated jacket encircling and spaced therefrom, a plurality of fluid circulating tubes extending longitudinally of and disposed within said casing, means for by-passing fluid from one group of tubes to another at one end of the casing, the other end of the casing having intake and discharge chambers communicating with said different groups of tubes, means for controlling intake and discharge of fluid with respect to said intake and discharge chambers, a heater disposed in said casing and arranged longitudinally with respect to said tubes, said heater and tubes being enveloped in a body of heat transmitting material, means providing access to opposed open ends of the circulating tubes without disturbing mounting of the several casing parts of the heater, and said last named means comprising plates having plugged openings in alignment with ends of the fluid circulating tubes.

3. A fluid heater of the character described, comprising a plurality of fluid circulating tubes having ends joined by tube plates, a body of insulating material completely enveloping the tubes intermediate said plates, another tube extending into and enveloped by said opening and opening outwardly through one of said plates for support of an electric heater to heat said body, headers secured to the tube plates controlling circulation of a fluid to be heated through said tubes, said headers having outwardly extending flanges of greater diameter than the diameter of said body of insulating material, a casing secured to the flanges and enveloping said body to form an insulating chamber therearound, insulation arranged in said chamber, said headers having apertures aligned with the ends of said tubes, plates detachable with respect to said headers, and said plates having plugged apertures aligned with the apertures of the header to facilitate cleaning-out of said circulating tubes.

4. A fluid heater of the character described, comprising a plurality of fluid circulating tubes having ends joined by tube plates, a body of insulating material completely enveloping the tubes intermediate said plates, another tube extending into and enveloped by said opening and opening outwardly through one of said plates for support of an electric heater to heat said body, headers secured to the tube plates controlling circulation of a fluid to be heated through said tubes, said headers having outwardly extending flanges of greater diameter than the diameter of said body of insulating material, a casing secured to the flanges and enveloping said body to form an insulating chamber therearound, insulation arranged in said chamber, said headers having apertures aligned with the ends of said tubes, plates detachable with respect to said headers, said plates having plugged apertures aligned with the apertures of the header to facilitate cleaning-out of said circulating tubes, one of said headers having an extension forming a chamber beyond the plate of said header, a detachable cover controlling access to said chamber, and said chamber being adapted to receive circuit wires extending to said electric heater.

5. A fluid heater of the character described, comprising a plurality of fluid circulating tubes having ends joined by tube plates, a body of insulating material completely enveloping the tubes

intermediate said plates, another tube extending into and enveloped by said opening and opening outwardly through one of said plates for support of an electric heater to heat said body, headers secured to the tube plates controlling circulation of a fluid to be heated through said tubes, said headers having outwardly extending flanges of greater diameter than the diameter of said body of insulating material, a casing secured to the flanges and enveloping said body to form an insulating chamber therearound, insulation arranged in said chamber, said headers having apertures alined with the ends of said tubes, plates detachable with respect to said headers, said plates having plugged apertures alined with the apertures of the header to facilitate cleaning-out of said circulating tubes, one of said headers having an extension forming a chamber beyond the plate of said header, a detachable cover controlling access to said chamber, said chamber being adapted to receive circuit wires extending to said electric heater, and to an aquastat exposed to the heat of said heat conducting body.

6. A fluid heater of the character described, comprising a plurality of fluid circulating tubes having ends joined by tube plates, a body of insulating material completely enveloping the tubes intermediate said plates, another tube extending into and enveloped by said opening and opening outwardly through one of said plates for support of an electric heater to heat said body, headers secured to the tube plates controlling circulation of a fluid to be heated through said tubes, said headers having outwardly extending flanges of greater diameter than the diameter of said body of insulating material, a casing secured to the flanges and enveloping said body to form an insulating chamber therearound, insulation arranged in said chamber, said headers having apertures alined with the ends of said tubes, plates detachable with respect to said headers, said plates having plugged apertures alined with the apertures of the header to facilitate cleaning-out of said circulating tubes, one of said headers having an extension forming a chamber beyond the plate of said header, a detachable cover controlling access to said chamber, said chamber being adapted to receive circuit wires extending to said electric heater, to an aquastat exposed to the heat of said heat conducting body, and an air coil arranged around at least a portion of said heat conducting body and directly exposed to heat radiating from said body.

7. A fluid heater of the class described, comprising a body of heat conducting material, means in said body forming a fluid circulating passage, through which a fluid to be heated is adapted to be passed, an air coil outwardly of said body, a casing enveloping the body and coil and spaced with respect thereto, the space of said casing having insulating material therein, a removable chambered member at the upper portion of said body with a removable cap closing the chamber of said member, an electric heating element arranged in said body and having terminal ends extending into said chamber, an aquastat arranged in said body and opening into said chamber, and means for directing circuit wires leading to the heating element and said aquastat out through said heater.

8. A fluid heater of the class described, comprising a body of heat conducting material, means in said body forming a fluid circulating passage, through which a fluid to be heated is adapted to be passed, an air coil outwardly of

said body, a casing enveloping the body and coil and spaced with respect thereto, the space of said casing having insulating material therein, a removable chambered member at the upper portion of said body with a removable cap closing the chamber of said member, an electric heating element arranged in said body and having terminal ends extending into said chamber, an aquastat arranged in said body and opening into said chamber, means for directing circuit wires leading to the heating element and said aquastat out through said heater, and said last named means comprising a conduit arranged in the insulation of the casing and opening into a junction box at the lower portion of the casing.

9. A fluid heater of the class described, comprising a body of heat conducting material, means in said body forming a fluid circulating passage, through which a fluid to be heated is adapted to be passed, an air coil outwardly of said body, a casing enveloping the body and coil and spaced with respect thereto, the space of said casing having insulating material therein, a removable chambered member at the upper portion of said body with a removable cap closing the chamber of said member, an electric heating element arranged in said body and having terminal ends extending into said chamber, an aquastat arranged in said body and opening into said chamber, means for directing circuit wires leading to the heating element and said aquastat out through said heater, said first named means comprising a series of tubes extending vertically in said body and opening through upper and lower ends thereof, a header at the lower portion of said body and casing, and said header being divided to form inlet and outlet chambers controlling circulation of fluid through said tubes.

10. A fluid heater of the class described, comprising a body of heat conducting material, means in said body forming a fluid circulating passage, through which a fluid to be heated is adapted to be passed, an air coil outwardly of said body, a casing enveloping the body and coil and spaced with respect thereto, the space of said casing having insulating material therein, a removable chambered member at the upper portion of said body with a removable cap closing the chamber of said member, an electric heating element arranged in said body and having terminal ends extending into said chamber, and aquastat arranged in said body and opening into said chamber, means for directing circuit wires leading to the heating element and said aquastat out through said heater, said first named means comprising a series of tubes extending vertically in said body and opening through upper and lower ends thereof, a header at the lower portion of said body and casing, said header being divided to form inlet and outlet chambers controlling circulation of fluid through said tubes, and means comprising a removable plate for forming a circulating chamber within said chambered member.
